BOTTLE

Henry B. Melamed, 78-40 164th St., Flushing, N.Y.
11366, and Joseph F. Cullen, 310 85th St., Brooklyn,
N.Y. 11209

Filed May 25, 1966, Ser. No. 2,436

Term of patent 14 years

(Cl. D58—8)

We claim:

The ornamental design for a bottle, as shown.
